UNITED STATES PATENT OFFICE.

JOSEPH KRATOCHVIL, OF CHICAGO, ILLINOIS.

MECHANISM FOR OPERATING RAILROAD-CROSSING GATES.

Application filed June 27, 1921. Serial No. 480,596.

To all whom it may concern:

Be it known that I, JOSEPH KRATOCHVIL, citizen of Austria-Hungary, residing at Chicago, in the county of Cook and State 5 of Illinois, have invented certain new and useful Improvements in a Mechanism for Operating Railroad-Crossing Gates; and I do hereby declare the following to be a full, clear, and exact description of the invention, 10 such as will enable others skilled in the art to which it appertains to make and use the same.

The object of the invention is to provide a comparatively simple and at the same time 15 relatively inexpensive and reliable means whereby railroad grade crossing gates may be closed and opened successively by and in the course of progress of a train or trains operating in opposite directions upon the same or different tracks without requiring the constant attention of flagmen or gate- 20 men at the crossings and under conditions providing for the safety of traffic on the intersecting or cross roads both with reference 25 to pedestrians and vehicles; and with these objects in view the invention consists in a construction, combination and relation of parts of which a typical embodiment is 30 illustrated in the accompanying drawings, wherein:

Figure 1 is a plan view of a double track intersected by two cross roads, at each of which is arranged a gate (which may, if preferred and as shown consist of two duplicate units) showing in connection therewith a gate operating mechanism embodying the invention with the wiring system in diagram.

Figure 2 is a cross sectional view showing one of the gates in elevation and partly broken away to indicate the housed mechanism employed in connection therewith.

Figure 3 is a side view,

Figure 4 is a plan view, and

Figure 5 is a wiring diagram of one 45 of the relays.

Figure 6 is a side view, with the casing broken away of one of the single way trips and the circuit closer mechanism employed in connection therewith.

Figures 7 and 8 are sectional views respectively on the planes indicated by the lines 7-7 and 8-8 of Figure 6.

Figure 9 is a view similar to Figure 8 showing the trip in its depressed position and the contacts engaged to close the track circuit.

Figure 10 is a side view of a double or two-way trip.

Figure 11 is a plan view of the same.

Figure 12 is an end view partly in section 60 thereof.

Figure 13 is a section taken on the plane indicated by the line 13-13 of Figure 12.

Figures 14 and 15 are respectively side 65 and end views of a trip operating shoe adapted to be carried by the locomotive or any suitable part of the rolling stock.

Generally considered the mechanism consists of train or car actuated trips arranged at suitable distances on the track on opposite 70 sides of an intersecting or cross road adjacent to which a gate is located and adapted to be successively operated to respectively close and open the gate, the operation of each trip serving to close a circuit which for convenience may be termed a track circuit of relatively low voltage current to operate a relay switch which in turn closes an operating circuit of relatively high voltage current to actuate the gate. In the construction 75 illustrated the gate is preferably constructed to normally occupy an open position in which it is held and to which it is returned, when released, by a counter weight or equivalent mechanical replacing device so that 80 the electrical mechanism serves through the first trip to move the gate from its open to its closed position and through the second trip to release the gate from the closing mechanism so that it may be returned by its 85 counterbalancing means to the open or normal position, but it will be understood that the relations of these elements and agencies 90 may be modified to suit peculiar conditions of traffic without departure from the spirit 95 or principle of operation herein disclosed.

As illustrated in the drawing the gate shown in elevation in Figure 2 is of the two-unit type having the arms 10 which are pivotally mounted in suitable posts or housings 11 at opposite sides of the intersecting roadway and are counterweighted as indicated at 12 to yieldingly hold the same in the open or upright position leaving the cross road free for traffic and serving to return 100 the arms to the said normal position when released. Carried by the bearing shafts 13 of these arms are pulleys 14 which through flexible connections 15 are actuatable to move the gate arms to their closed or operative 105 positions by the cores 16 of solenoids 17 included in the operating circuit 18 of rela-

tively high voltage and under the control of the relays 19 and 19^a shown in detail in Figures 3, 4 and 5 and in diagrammatic assembly in Figure 1.

5 In the construction illustrated two relay switches, similarly constructed are arranged in operative relation with each gate for the reason, as will be more particularly explained hereinafter, that it is desirable to 10 employ a relay for each track of which two designated respectively as track A and track B are shown in the drawing, track A being equipped for traffic in both directions while track B is equipped for traffic in only one direction. Reference to the diagram Figure 1 will show the location of the track trips respectively at a, b, c, d, e and f for track A and at g, h, and i for track B so that as a train 15 proceeds in the direction of the arrow on either of the tracks the proper trips will be operated and hence through one of the relays will close the operating circuit to operate the gate 1 and move it to a closed position, and when the train reaches the trip at station b it 20 will operate the track circuit to actuate the relay and thereby open the operating circuit of gate number 1 which was previously closed and at the same time will operate through the connections including one of the relays 25 of gate number 2 to close the latter, and then proceeding further until it reaches station c, the train will actuate the trip to open the gate number 2, thus successively closing and opening the gates as it proceeds and obviously operating in a corresponding manner with reference to any required number of gates which may be arranged in series. The operation of the circuits more in detail will be set forth hereinafter. Moreover the 30 relays which are hereinafter described in detail, are so constructed that the reverse operation will occur upon the movement of a train on the track in the opposite direction, so that upon reaching the trip at station 35 c the gate number 2 will be closed, upon reaching station b the gate number 2 will be released and gate number 1 will be closed, and upon reaching station a the gate number 1 will be released.

50 In Figures 3, 4 and 5 there is shown a relay constructed to carry out the object of the invention, the same having a plurality of two pole electromagnets of which that indicated at 20 is included in the operating circuit 21 with the contacts 22 and 23, of which the former is carried by an armature 24 yieldingly held out of contact with the magnet by means of the spring 24^a or its equivalent, this switch being of the pick-up type 55 so that it breaks the operating circuit when the coil 20 is deenergized, and when the operating circuit is closed the magnet 20 serves to maintain it in a closed condition.

The magnet 25 also forming a member 60 of the relay 19 or 19^a, is included in the

track circuit 26 or 26^a, in which a very low voltage current may be employed, and when a trip is operated to close the circuit the magnet 25 attracts the armature 24 and thereby closes the operating circuit 21 70 through the engagement of the contacts 22 and 23. The armature 24 however forms a part of the operating circuit connected by a coupling element or bridge 27 with a supplemental armature 28 which operates in connection with a third electromagnet 29 included in the track circuits 26 and 26^a, said auxiliary armature 28 being yieldingly held by means of a spring 30 with a terminal contact 31 thereof in engagement with a contact 32 to complete the operating circuit at this point, so that normally it is broken only at the contacts 22 and 23, and when the contacts 22 and 23 are brought into engagement the operating circuit is 80 completed as hereinabove described. However, when the track circuit 26 through the trip at station b is closed through the magnet 29 to attract the supplemental armature 28, the operating circuit which passes through contacts 31 and 32 is broken at the contacts 31 and 32 to open the operating circuit and thereby deenergize the solenoids 17 to release and permit the return of the gate to its normal or open position. The contacts and stops consist of suitably adjustable elements to permit of proper relative arrangement thereof to suit the conditions of operation and insure accuracy, as for example the contact 32 is carried by adjusting screw 33 having a suitable lock nut 34, the stop 35 consists of a screw designed to limit the return or circuit opening movement of the armature arm 24, the same also having a lock nut 36, and the contact 23 is carried by a pin 37 having an actuating spring 38 and engaged by a stop nut 39.

Also in order to prevent an arc at the contacts 31, 32 when the operating circuit is opened at that point by the closing of the track circuit through a trip at the station b, a high capacity condenser 40 is shunted across the contacts by connection through the wires 41 respectively with the standards 42 and 43 upon the former of which rests the spring 30 in contact with the auxiliary armature arm 28 while the latter carries the contact 32.

Obviously various types of trips may be employed in connection with the mechanism hereinabove described but it is desirable that whatever type is used in this connection should be of such a character as to provide not only for a return to the initial position after being encountered or operated by a passing train but to maintain the track circuit in a closed condition for appreciable and sufficient length of time to permit of the proper operation of the relays 19 or 19^a so that the operating circuit 21 may be prop- 120 125 130

erly closed, the construction of the relay itself being such that when once closed as above described the operating circuit 21 serves to maintain the magnet 20 in an energized condition and thus hold the armature 24 in its circuit closing position. To this end the trip which is shown in detail in Figures 6, 7, 8 and 9 consists of a rocker 44 pivoted as at 45 in the path of a suitable object on the train or car such, for example, as the foot or shoe 46, shown in detail in Figures 14 and 15 and having an anti-friction roller 47, the shank 46^a being adjustable to properly position the shoe with relation to the rocker. The rocker is returnable to its elevated position by means of coiled cushioning springs 49 or the equivalent thereof arranged for example between upper and lower bars 50 and 51 around suitable guiding pins 52, said bars respectively carrying the contacts 53 and 54 adapted to be brought into engagement by the depression or operation of the rocker. In connection with the rocker there is employed a restraining device consisting of a ratchet arm 55 carried by the rocker for engagement with a ratchet wheel 56 on the shaft 57 of which is arranged a fly wheel 58 preferably comprising a plurality of disks as shown in Figure 7, the ratchet bar being yieldingly held in engagement with the ratchet wheel by means of a spring 59. When the rocker is operated or depressed, therefore, the ratchet bar slips over the teeth of the ratchet wheel 56 and when relieved of pressure by the shoe or operating element carried by the train or car, the tendency of the cushion springs 49 to return the rocker is opposed by the restraining device which through the ratchet bar 55 and the ratchet wheel 56 involves the rotation of the shaft 57 carrying the fly wheel. Obviously the starting of the rotary movement of the fly wheel is relatively slow and as the rocker can return to its elevated or normal position only through a suitably protracted rotation of the shaft 57 the restoration thereof may be retarded to any desired or practical extent. Moreover this operation of prolonging the engagement of the contacts 53 and 54 and hence the closed condition of the track circuit 26 or 26^a through the magnet 25 is insured by the fact that the contact 54 is carried by a follower pin 60 provided with an actuating spring 61 and operating in a suitable guide opening 62 in the lower bar 51, the contact being arranged in a cylindrical guide 63 carried by the upper bar 50 in which the contact 53 is arranged. When the rocker is depressed the first movement thereof is to bring the contact 53 into engagement with the contact 54 and the further movement of the rocker depresses the contact 54 against the action of the spring 61. When the rocker is relieved of pressure and commences its upward or return movement, the contact 54 through the action of the spring 61 follows the same for a considerable distance and in fact until the rocker has almost reached the upper limit of its movement before the engagement between the contacts 53 and 54 is broken and the track circuit thereby opened.

In connection with the gate, it is preferable to use an audible signal such as a bell 75 and a visual signal such as a lamp 89, both of which can be actuated by the operating current by arranging the same in series therewith as indicated by the conductors 90 in the diagrammatic showing of Figure 1. In operation and specifically tracing the circuits through the various conductors shown, say a train is travelling from left to right in Figure 1, no effect on the gate is had as roller 47 depresses trips 44 at the stations *f*, *e* and *d* in the order named. However when roller 47 depresses trip 44 at station *a*, a circuit is closed through the relay 19 of gate No. 1, namely through the contacts 53 and 54, conductors 91 and 92, magnet 25, conductors 93 and 94, a source of low voltage current 95, a conductor 96, a conductor 97, and a conductor 98. Thus magnet 25 is energized and attracts armature 24 which closes the higher voltage circuit namely from a source 99 through conductor 96, a conductor 100, a conductor 101, shunt wires 41, condenser 40, contacts 31 and 32, armature 28, bridge 27, armature 24, contacts 22 and 23, coil 20, a conductor 102, conductors 103 and 104, magnets 17, conductors 105 and 90, lamp 89, bell 88 and conductor 106 back to the source. Magnets 17 being energized, their cores 16 are retracted to draw elements 15 and thus lower the arms 10 of gate 1 and maintain them lowered. The same action occurs for the gate No. 2 through the relay 19 of that gate when contacts 53 and 54 at *b* are bridged by its trip 44 through actuation of roller 47. Also when said contacts are bridged at *b*, a circuit is completed through magnet 27 of gate No. 1 from source 95, that is from said contacts 53 and 54 at *b* through a conductor 107, a conductor 108, magnet 29, conductor 93, conductor 94, source 95, conductor 96, conductor 97 and conductor 98, back to said contacts. Magnet 29 being thus energized attracts the adjacent armature 28 which disengages contacts 31 and 32 and breaks the circuit through magnet 20 of relay 19 of gate No. 1 so that the arms 10 thereof will be released and will raise under urgency of the weight 12 thereof. In the same manner the magnet 29 of relay 19 for gate No. 2 will open the circuit of magnet 20 thereof when the circuit at *c* is closed. If a train on track A travels from right to left in Figure 1, the trip at *d* will close gate No. 2, the trip at *e* will open gate No. 2 and close gate No. 1 and the trip at *f* open gate 130.

No. 2 through the circuits which will be obvious in view of those traced, and through which movement the trips at *a*, *b* and *c* will be inutile. Thus as a train moves in either 5 direction it will automatically cause each gate to lower as it approaches the adjacent crossing and to raise after passing such crossing.

If a train travels on track B in the direction of the arrow, the circuit will be controlled through the relays 19^a. Thus if the contacts at *g* are bridged, a circuit for gate 1 is completed through a conductor 108, the magnet 25, conductor 94, source 95, conductor 15 96, a conductor 109 and a conductor 110. Thus the adjacent magnet 20 is energized and the circuit through source 99 is completed as previously set forth. When the contacts at *h* are closed, a circuit in the same 20 manner is closed through magnet 25 of relay 19^a of gate No. 2 and in addition, the current travels from the contacts at *h* through magnet 29 of relay 19^a of gate No. 1, conductor 94, source 95, conductor 96, conductor 109, and a conductor 112, thus energizing magnet 29 and breaking the circuit through magnets 18 of gate 1. Similarly the circuit for magnets 17 of gate No. 2 will be 25 broken if trip *i* is bridged.

30 In a modified construction of treads illustrated in Figures 10 to 13 inclusive, designed for operation in either direction, the rocker 64 is pivotally mounted at 65 and carries a cross arm 66 which supports the ratchet bars 35 67 in engagement with the ratchet wheels 68 for operating the fly wheels 69. The lower extremities or free ends of the ratchet bars are deflected as indicated at 70 to insure the proper return of each arm to its proper engaging relation with the cooperating ratchet wheel after the trip has been moved in the opposite direction to thereby cause disengagement of the first named arm with its ratchet. In other words when for example 40 the rocker is moved in the direction indicated by the arrow in Figure 10 the ratchet bar at the left serves as a means for restraining the return movement of the trip while the ratchet arm at the right is elevated and carried out of engagement with its ratchet, but as the trip returns to its normal position the deflected extremity 70 of the second 45 named arm slides over the ratchet until it reaches the operative position indicated in 50 Figure 10. The actuating springs 71 for the ratchet arms serve to swing the arms inward or toward their respective ratchet wheels but the inward swinging movement of said arms is limited by the shoulders formed 55 by the ends of the cross arm 66.

In this construction of trip, in order to prevent access of water to the interior mechanism enclosed by the housing 72, the shank 73 of the trip is bifurcated or forked 60 as shown at 74, the shank passing through

a slot 75 in an inner deck 76 of the wall of the housing and the arms of the fork passing through slots 77 in the outer deck of said wall, the slots 77 being laterally out of the vertical plane of the slot 75 and the deck 76 being guttered or channeled or having an upturned inner edge as indicated at 78 to prevent water which may enter through the slots 77 from passing through the slot 75.

The contact operating features of the double trip shown in Figures 10 to 13 inclusive correspond in general construction with that previously described in that they include the rocker arm 80 of which the extremities are adapted for depression respectively of the bars 81 having the return or cushion springs 82 seated at their lower ends on the stationary bars 83 and also carrying the movable contact pins 84 for engagement with the stationary contacts 85 having guide pins 86 upon which are fitted return springs 87. It will now be obvious that the desirability of having a relay for each track resides in the fact that should two trains moving in opposite directions upon the tracks approach the same gate or series of gates at about the same time, the train on the track B however slightly in advance of the train on track A, or somewhat nearer to the crossing, the first to reach the gate releasing trip, at station *b* for example, would close the gate number 1 and open the gate number 2, while the other reaching station *b* before the train on track B has reached the gate number 2 would tend to open or release the gate number 2 and thus expose the traffic on the cross road protected by gate number 2 to train on track B were it not for the separate relay arrangement which insures the closing of gate number 2 by the action of the train on track B.

Having thus described the invention, what I claim is;

1. A railway gate operating mechanism having a solenoid connected with the gate, an operating circuit including the solenoid, a relay switch for controlling said circuit and a track circuit for actuating the relay and including a trip actuated circuit closer for operation by the rolling stock, said relay having a magnet included in the operating circuit and an armature forming an element of the operating circuit.

2. A railway gate operating mechanism having a solenoid connected with the gate, an operating circuit including the solenoid, a relay switch for controlling said circuit and a track circuit for actuating the relay and including a trip actuated circuit closer for operation by the rolling stock, said relay having a magnet included in the operating circuit and an armature forming an element of the operating circuit, and also having magnets included in the track circuit and

armatures for respectively closing and opening the operating circuit.

3. A railway gate operating mechanism having a solenoid connected operatively with a gate yieldingly held in a normal position, an operating circuit including the solenoid, a relay switch for controlling said circuit and track circuits for actuating the relay and respectively including trip actuated circuit closers for operation by rolling stock, said relay having an electromagnet included in the operating circuit and an armature forming an element of the operating circuit and sensitive to said magnet for maintaining the operating circuit in a closed condition, and also having electromagnets included respectively in said track circuit and provided with contact controlling armatures for respectively closing and opening the operating circuit.

4. A railway gate operating mechanism having a solenoid connected operatively with a gate yieldingly held in a normal position, an operating circuit including the solenoid, a relay switch for controlling said circuit and track circuits for actuating the relay and respectively including trip actuated circuit closers for operation by rolling stock, said relay having an electromagnet included in the operating circuit and an armature forming an element of the operating circuit and sensitive to said magnet for maintaining the operating circuit in a closed condition, and also having electromagnets included respectively in said track circuit and provided with contact controlling armatures for respectively closing and opening the operating circuit, one of the second named armatures being common to the armature of the magnet included in the operating circuit.

5. A railway gate operating mechanism having a solenoid connected operatively with a gate yieldingly held in a normal position, an operating circuit including the solenoid, a relay switch for controlling said circuit and track circuits for actuating the relay and respectively including trip actuated circuit closers for operation by rolling stock, said relay having an electromagnet included in the operating circuit and an armature forming an element of the operating circuit and sensitive to said magnet for maintaining the operating circuit in a closed condition, and also having electromagnets included respectively in said track circuit and provided with contact controlling armatures for respectively closing and opening the operating circuit, said armatures being yieldingly held respectively in circuit opening and circuit closing position.

6. A railway gate operating mechanism having a solenoid connected operatively with a gate yieldingly held in a normal position, an operating circuit including the solenoid, a relay switch for controlling said

circuit and track circuits for actuating the relay and respectively including trip actuated circuit closers for operation by rolling stock, said relay having an electromagnet included in the operating circuit and an armature forming an element of the operating circuit and sensitive to said magnet for maintaining the operating circuit in a closed condition, and also having electromagnets included respectively in said track circuit and provided with contact controlling armatures for respectively closing and opening the operating circuit, a condenser being shunted across the normally closed contact.

7. A railway gate operating mechanism having a solenoid connected with the gate, an operating circuit including the solenoid, a relay switch for controlling said circuit and a track circuit for actuating the relay and including a trip actuated circuit closer for operation by the rolling stock, said relay having magnets respectively included in the operating and track circuit and a common armature for the same forming an element of the operating circuit, and reluctant means for retarding of the trip actuated circuit closer.

8. A railway gate operating mechanism having a solenoid connected with the gate, an operating circuit including the solenoid, a relay switch for controlling said circuit and a track circuit for actuating the relay and including a trip actuated circuit closer for operation by the rolling stock, said relay having magnets respectively included in the operating and track circuit and a common armature for the same forming an element of the operating circuit, said trip having a movable rocker and reluctant means for retarding the return of the rocker to its normal position.

9. A railway gate operating mechanism having a solenoid connected with the gate, an operating circuit including the solenoid, a relay switch for controlling said circuit and a track circuit for actuating the relay and including a trip actuated circuit closer for operation by the rolling stock, said relay having magnets respectively included in the operating and track circuit and a common armature for the same forming an element of the operating circuit, said trip having a movable rocker and reluctant means for retarding the return of the rocker to its normal position, and including a fly wheel and means for communicating motion thereto during the return movement of the rocker.

10. A railway gate operating mechanism having a solenoid connected with the gate, an operating circuit including the solenoid, a relay switch for controlling said circuit and a track circuit for actuating the relay and including a trip actuated circuit closer for operation by the rolling stock, trip mechanism having a rocker and reluctant means

for retarding the return movement thereof, the same including a fly wheel having a ratchet wheel and a ratchet bar carried by the rocker for engagement with said ratchet wheel during the return movement of the rocker.

11. A railway gate operating mechanism having a solenoid connected with the gate, an operating circuit including the solenoid, 10 a relay switch for controlling said circuit and a track circuit for actuating the relay and including a trip actuated circuit closer for operation by the rolling stock, trip mechanism having a rocker and reluctant means 15 for retarding the return movement thereof, the same including a fly wheel having a ratchet wheel and a ratchet bar carried by the rocker for engagement with said ratchet wheel during the return movement of the 20 rocker, said ratchet arm being yieldingly impelled toward the ratchet wheel.

12. A railway gate operating mechanism having a solenoid connected with the gate, an operating circuit including the solenoid, 25 a relay switch for controlling said circuit and a track circuit for actuating the relay and including a trip actuated circuit closer for operation by the rolling stock, said trip consisting of a rocker operatively movable 30 in opposite directions from a neutral position, and reluctant means for retarding the return of the rocker to its neutral position.

13. A railway gate operating mechanism having a solenoid connected with the gate, an operating circuit including the solenoid, 35 a relay switch for controlling said circuit and a track circuit for actuating the relay and including a trip actuated circuit closer for operation by the rolling stock, said trip 40 consisting of a rocker operatively movable in opposite directions from a neutral position, reluctant means for retarding the return of the rocker to its neutral position consisting of revoluble, resistance offering 45 ratchet wheels and ratchet bars carried by oppositely directed arms of the rocker for respective engagement with said ratchet wheels.

14. A railway gate operating mechanism 50 having a solenoid connected with the gate, an operating circuit including the solenoid, a relay switch for controlling said circuit and a track circuit for actuating the relay and including a trip actuated circuit closer 55 for operation by the rolling stock, said trip consisting of a rocker operatively movable in opposite directions from a neutral position, reluctant means for retarding the return of the rocker to its neutral position consisting 60 of revoluble, resistance offering ratchet wheels and ratchet bars carried by oppositely directed arms of the rocker for respective engagement with said ratchet wheels, and arranged for communicating motion there-

to during opposite movement of the rocker. 65

15. A railway gate operating mechanism having a solenoid connected with the gate, an operating circuit including the solenoid, a relay switch for controlling said circuit and a track circuit for actuating the relay 70 and including a trip actuated circuit closer for operation by the rolling stock consisting of a rocker and normally separated contacts, one of which is carried by the rocker and the other of which is movable by and in the direction of the first-named contact and is depressed thereby and thereafter yieldingly impelled in opposition thereto during part 75 of the return movement of the rocker.

16. A railway gate operating mechanism having a solenoid connected with the gate, an operating circuit including the solenoid, a relay switch for controlling said circuit and a track circuit for actuating the relay 80 and including a trip actuated circuit closer for operation by the rolling stock, and consisting of a rocker and normally separated contacts, one of which is carried by the rocker and the other of which is yieldingly mounted in the path of the former for depression thereby and movement thereafter during part of the return movement of the 85 rocker.

17. A railway gate operating mechanism having a solenoid connected with the gate, an operating circuit including the solenoid, a relay switch for controlling said circuit and a track circuit for actuating the relay and including a trip actuated circuit closer 90 for operation by the rolling stock, and consisting of a rocker and normally separated contacts, one of which is carried by the rocker and the other of which is yieldingly held in the path of and is movable by and with the former during portions of the forward and return movement thereof. 95

18. A railway gate operating mechanism having a solenoid connected with the gate, an operating circuit including the solenoid, a relay switch for controlling said circuit and a track circuit for actuating the relay and including a trip actuated circuit closer 100 for operation by the rolling stock, and consisting of a rocker and normally separated contacts, one of which is carried by the rocker and the other of which is yieldingly held in the path of and is movable by and with the former during portions of the forward and return movement thereof, and 105 reductant means for retarding the return 110 movement of the rocker.

In testimony whereof I affix my signature in presence of two witnesses.

JOSEPH KRATOCHVIL.
